Primary Examiner — T. Chase Nelson*Assistant Examiner* — Mark Cavanna(74) *Attorney, Agent, or Firm* — Knobbe Martens Olson & Bear LLP(57) **CLAIM**

The ornamental design for an inversion plate, as shown and described.

DESCRIPTION

FIG. 1 is a perspective view of an inversion plate in accordance with the present invention.

FIG. 2 is a top view of inversion plate of FIG. 1.

FIG. 3 is a bottom view of inversion plate of FIG. 1.

FIG. 4 is a front view of the inversion plate of FIG. 1.

FIG. 5 is a cutaway view of the inversion plate of FIG. 1, taken along line 5-5.

FIG. 6 is a back view of the inversion plate of FIG. 1.

FIG. 7 is a left end view of the inversion plate of FIG. 1; and, FIG. 8 is a right end view of the inversion plate of FIG. 1.

Broken lines are used to illustrate features of the inversion plate which form no part of the claimed design.

1 Claim, 5 Drawing Sheets---
